UNITED STATES PATENT OFFICE.

ROBERT J. WALKER, OF PHILADELPHIA, PENNSYLVANIA.

CLOTH-STEAMING BOX.

SPECIFICATION forming part of Letters Patent No. 257,792, dated May 9, 1882.

Application filed January 12, 1882. (No model.)

To all whom it may concern:

Be it known that I, ROBERT J. WALKER, a citizen of the United States, residing in Philadelphia, Pennsylvania, have invented certain 5 Improvements in Cloth-Steaming Boxes, of which the following is a specification.

My invention relates to an improvement in the steaming-boxes used in connection with calendering and other machines for reducing 10 fabrics passed through the box to a proper condition for being acted upon by the said machines; and the objects of my invention are, first, to prevent the spotting of the fabrics by drops of water of condensation in the steaming-box; second, to economize the consumption 15 of steam; and, third, to economize space.

In the accompanying drawings, Figure 1 is a vertical section of the ordinary steaming-box used in connection with calendering-machines; Fig. 2, a vertical section of a calendering-machine combined with my improved steaming-box; Fig. 3, a perspective view of the steaming-box, drawn to an enlarged scale; and Fig. 4, a view of one of the bearings of the 5 roller in the box.

The ordinary steaming-box shown in Fig. 1 consists of a quadrangular structure forming an inclosed chamber, to which steam is admitted through a pipe, *a*, near the bottom of 30 the box, while the fabric *x* to be steamed prior to being calendered passes horizontally through slots made in the front and rear of the box. The main objection to this steaming-box is the accumulation of the water of condensation on 35 the under side of the top of the box and the dropping of the water therefrom onto the fabric, these drops having the effect of making on the fabric spots which cannot be removed.

In order to overcome this difficulty, I construct the box and combine it with a calendering-machine in the manner shown in Fig. 2, A being the steaming-box, and B the calendering-machine, which may be constructed in the usual manner, with three rollers, *d*, *d'*, and 40 *d''*, the journals of which are adapted to bearings in side frames, which are furnished with appliances for imparting the necessary pressure to these rollers. The front *e* and back *e'* of the box converge from the base *f* to their 45 upper termination, where they are a short distance apart from each other, so as to present an elongated opening, through which the fabric

x passes downward over and in contact with the upper edge of the front *e*, and upward and in contact with the upper edge of the rear *e'* of the box, the opening in the top of the same being of just sufficient width to permit the escape of the waste-steam and prevent the contact of the descending with the ascending fabric. 55

A roller, *G*, round which the fabric passes, 60 is contained within the lower portion of the box, and has journals adapted to suitable bearings formed in the same. I prefer to make these bearings in the manner shown in Fig. 4—that is, in strips *h*—one secured to the inner 65 side of each end of the box, each bearing being at one end of a horizontal slot, *i*, the other end, *j*, of which extends vertically through the upper edge of the strip. The fabric which 70 passes round this roller is always under more or less tension, and therefore tends to keep the journals of the roller in their bearings; but in the absence of the fabric the journals of the 75 roller can be withdrawn from their bearings and the roller removed from the box after first opening the door *I* of the same.

A steam-pipe, *J*, passes downward into the box and extends horizontally near the bottom, the horizontal portion being perforated, and the pipe being furnished with a suitable cock 80 for admitting the desired quantity of steam to the box. As the fabric passes downward into the box and upward from the roller *G*, it is subjected on both sides to the action of steam, and as the water of condensation will flow down 85 the converging front and rear of the box, there can be no dropping of water onto the fabric.

A further advantage of my improved box is the small amount of room which it occupies 90 compared with that which the old quadrangular box demands, and still further advantages are the large surface of fabric exposed to the steam, and the limited quantity of steam required to produce the desired effect on said fabric.

In the present instance the rear of the box is vertical and the front inclined; but the rear also may, if desired, be slightly inclined. Whatever change may be made in the form of the box, it must be wide enough below to admit the roller, and must converge at the top to form the contracted opening for the passage of the fabric. 95

Suitable provision is made for carrying off 100

the water of condensation from the bottom of the box.

Although I have shown my invention as used in connection with a calendering-machine, it will be evident that it can be used in connection with other machines where a preliminary steaming of the fabric is advisable.

I claim as my invention—

1. The combination of a steaming-box having at the top an elongated opening, with a pipe for admitting steam to the box, and with a roller whereby the fabric is directed downward and upward through the said opening and in the course described within the box, all substantially as set forth.

15 2. The within-described steaming-box, hav-

ing converging front and rear and an elongated opening in the top, in combination with a roller, G, and a steam-pipe, J, substantially as described.

20 3. A steam-box provided with door I, roller G, and slotted bearings *i j*, whereby the said roller may be readily removed, all being combined substantially as set forth.

In testimony whereof I have signed my name 25 to this specification in the presence of two subscribing witnesses.
